Application May 25, 1931, Serial No. 539,730

18 Claims. (Cl. 8—19)

This invention relates to the treatment of thread and more particularly to an improved apparatus suitable for conveniently washing or otherwise treating threads wound upon bobbins or spools or other receivers. In describing the invention reference will be made to its use in connection with the treatment of artificial silk threads made according to the viscose process but it is not intended to thereby limit it to the particular use described since it will be apparent that it may be used to advantage in washing and treating artificial threads produced by other processes and in otherwise treating threads.

In the production of threads by the viscose process the viscose solution is forced from the spinnerette into a suitable precipitating bath which is usually an acid bath containing dissolved salts. The precipitated thread is subsequently subjected to a washing step to remove any of the fixing solution remaining upon the thread, after which it is ordinarily subjected to a desulphurizing solution, such as a solution of ammonium sulphide, and to subsequent washing and bleaching operations to produce the finished thread.

It is an object of this invention to provide an improved apparatus in which the threads may be conveniently subjected to a plurality of such washing or treating solutions, subsequent to the precipitation step. A further object is to provide a convenient arrangement of apparatus whereby different liquids may be conducted to and withdrawn from a washing tank without danger of mixing the several solutions. Another object is to provide an improved locking means for preventing accidental movement of the feed and discharge pipes while the system is in operation. Other objects will become apparent.

In describing the invention reference will be made to the drawings in which Figure 1 is a side elevation of the improved apparatus. Figure 2 is an end elevation of the apparatus shown in Figure 1, looking from the right. Figure 3 is a section taken on the lines 3—3 of Figures 1 and 2. Figure 4 is a sectional view taken on the line 4—4 of Figure 3. Figure 5 is a detailed section taken on the line 5—5 of Figure 3. Figure 6 is a fractional section taken on the line 6—6 of Figure 5. Figure 7 is a diagrammatic view of the vacuum system. Figure 8 is a vertical section through the filling pipe. Figure 9 is a vertical section through the swivel joint.

In the several drawings the numeral 10 designates a tank within which the thread is to be treated. The several liquids used in washing or

treating the thread in the tank 10 of each unit are conducted from separate storage tanks 10a for these liquids through the filling lines 11a, 11b and 11c, etc., having branches 12a, 12b and 12c, etc. with shut off valves 13a, 13b and 13c, etc., said branches extending downwardly to provide outlets positioned on an arc of a circle described about a point above the pivot 14.

A pipe 15 is supported by the frame 16 which may be pivoted about the pin 14. The upper end 10 of the pipe 15 is provided with a sleeve 17 having a flared upper end and adapted to telescope within the pipe 15. A handle 18, as illustrated more clearly in Figure 8 is pivotally mounted at 19 on the support 20, which is clamped to the 15 pipe 15. The inner bifurcated ends of the handle 18 provide arms 21, 21 carrying inwardly extending pins upon which the rollers 21a and 21a, positioned between the flanges 22 and 23 fixed to the sleeve 17, rotate.

The lower end of the sleeve 17 carries a pin 24 about which the upper end of a rod 25 is bent to provide an elongated slot 26 within which the pin 24 will slide when the sleeve is moved downwardly from its normal position. When the sleeve 17 is raised the pin 24 will engage the hook at the top of the rod 25 to lift that rod. The rod 25 passes through the pipe 15 and is provided with a hook 27 at its lower end that engages an eye in the valve 28 extending into 30 and covering the outlet 29 of the T fitting at the lower end of the pipe 15. A pin 18a, which may be passed through one of the three holes 18b in the support 20 and a hole in the handle 18 which registers with one of said holes in its raised, 35 lowered and normal position, serves to retain the handle and the sleeve 17 in the desired position.

The horizontally extending outlet 30 of the T fitting at the end of the pipe 15 communicates with the hole 31 in the bottom of the tank 10 through a pipe 32, a swivel connection positioned below the pivot 14, and a pipe 33. As indicated more clearly in Figure 9, this swivel connection comprises an annular plate 34 which fits around the end of the downwardly projecting 45 L fitting 35 at the end of the pipe 33 and which rests upon the outwardly turned flange of the upwardly projecting L fitting 37 at the end of the pipe 32 and is held there by countersunk bolts 38 so as to hold an inwardly extending annular washer 39 of rubber or other suitable material. This ring is also provided with an annular depression adapted to receive the flange 36, which is fixed to the L fitting 35, and has upwardly and downwardly extending annular pro- 55

5 jections 34b, 34b at its outer edge. The above described portion of the swivel connection is then slipped over the end of the L fitting 35 to the position shown in the drawings so that the inside portion of the washer 38 is depressed as illustrated. A split ring 34a is fitted around the L fitting 35 above the flange 36 and is bolted to the ring 34 by bolts 38a. With the arrangement shown the ring 34a may slide on the flange 36 10 when the pipe 32 is pivoted about the swivel connection and the rubber washer 38 forms a seal which prevents the liquid from leaking through the swivel joint.

15 The tank 10 is provided with numerous outlets 40, 40 each connected to one of the several lateral manifolds 41, 41 extending across the tank beneath the rows of outlets. The manifolds 41, 41 are also each connected by a pipe 42 to a longitudinal manifold 43 extending beneath the several lateral manifolds and closed at one end. The 20 other end of the manifold 43 is connected to an auxiliary tank 44 by a pipe 45 extending through the bottom of the tank 44 to above the normal level of the liquid in this tank. A vacuum line 46, having a shut off valve 47 and a check valve 48, connects the upper portion of the tank 44 with the main vacuum system, comprising a tank 49 exhausted by a vacuum pump 50 and provided with a discharge pump 51 for withdrawing any 25 liquid that may accidentally be drawn into it 30 through the vacuum lines.

35 A float 52, is connected by a stem to a switch 53, adapted to make and break an electric contact, so that when the float is in a raised position an electric motor 54, which drives a suction pump 55 connected to the bottom of the tank 44, will be started. When the float has lowered the desired amount the pump 55 will be shut off. This pump 55 is regulated to draw a vacuum of about 40 25 inches of mercury as compared to about 12 to 20 inches of mercury in the main vacuum system to which the line 48 is connected and the liquid discharges through the flexible or swiveled 45 connected line 56, the outer end of which is fixed to the lower end of the pipe 15. A check valve 57 is provided in the line 56 to close that line when the pump 55 is not in operation.

50 Drain lines 58a, 58b and 58c, etc., lead the liquids discharged from the tank 10 to separate tanks for the liquids to be saved or reused or regenerated for reuse, and to the sewer for liquids to be discarded. These drain lines are provided with receiving ports 59a, 59b and 59c, etc., which are positioned directly beneath the outlet of the 55 pipe 15 and the line 56 when the pipe 15 is connected to filling lines 11a, 11b and 11c, etc., respectively.

60 The tank 10 is provided with a vertical baffle 60 extending across the tank from its top to within a short distance of its bottom. A horizontal baffle 61 is fixed to the baffle 60 near its lower end and extends over the inlet 31.

65 At one side of the end compartment formed by the baffle 60 an overflow pipe 62 is provided through which any excess of liquid in the tank 10 may be discharged. At the other end of this end compartment a float 63 is positioned in a well 64 in the bottom of the tank 10. A flexible cable 65 is fixed at one end to the float 63 and at 70 its other end to a pin 66 so that a vertical movement of the float 63 will move the pin 66 horizontally through the guide 66a, toward and from the sleeve 11. The length of the cable 65 is such that when the float 63 is at its maximum height, 75 governed by the casing 67, the locking pin 66 will

be advanced toward the sleeve 11 a sufficient distance to obstruct the downward movement of the flange 22 and so prevent downward movement of the sleeve 11. When the float 63 is in its lowest position the pin 66 will be withdrawn sufficiently 5 to escape the flange 22 in order to permit the sleeve 11 to be lowered when the tank 10 and the well 64 are empty. The pipe 15 may be then moved to another filling line.

10 As an illustration of the operation of the apparatus described, the filaments from a viscose spinning operation may be wound directly upon 15 perforated receivers which may be placed in tiers of three or more in the tank 10, a cap 68 and annular gaskets 69, 69 of rubber or other suitable material being provided to cause all of the liquid withdrawn through the outlets 40, 40 to pass through the filaments and the perforations in the bobbins. The handle 18 is then raised to 20 depress the sleeve 11 and the pipe 15 is swung to 25 beneath the outlet of the branch pipe 12a connected to the water supply. The handle 18 is then returned to its normal position whereby the sleeve 11 is raised so as to surround or connect with the outlet of the pipe 12a. The valve 13a 25 may then be opened and water allowed to enter the tank through the pipes 15, 32 and 33. The baffles 60 and 61 will prevent surging of the liquid 30 through the tiers of bobbins, which surging might derange the tiers of bobbins.

35 When the tank 10 is filled to above the level of the caps 68, the valve 13a is partially shut off and the valve 47 in the vacuum line is opened. The relative rate of flow of liquid through the valves 13a and 47 is regulated so that the level 40 of liquid in the washing tank 10 is maintained substantially constant. The liquid is drawn through the filaments and the perforations in the bobbins and into the tank 44 under a vacuum. This tank 44 serves to separate the gases 45 from the liquid and when the level of liquid in the tank 44 reaches such a height as to raise the float 52 sufficiently to start the motor 54, the liquid will be discharged into the opening in the drain line 59a, which opening is directly beneath 45 the outlet of the pipe 15 when connected to the filling line 12a. The check valve 48 will be closed and the check valve 57 will be opened by the higher suction of the pump 55. When the level 50 of the liquid in the tank 44 has lowered the desired amount, the float 52 will cut off the motor 54, the check valve 57 will close, and the check valve 48 will open to draw more liquid from the tank 10.

55 This operation is continued for example for about 2½ to 3 hours or until the treatment is completed. The valve 13a is then shut off and the handle 18 is lowered to open the discharge valve 28 at the bottom of the pipe 15. The liquid in the tank 10 will flow out through the pipes 32 and 33 and into the proper drain line. When the tank 10 and well 64 are completely drained the float 63 will lower and the lock pin 66 will be withdrawn. The handle 18 may now be raised to 60 lower the sleeve 11 so that the pipe 15 might swing to the next filling line 12b, whereupon the operation may be repeated with another treating liquid.

65 During the above operation the liquid may be 70 emptied through the drain valve 28 alone, or the suction through the auxiliary tank 44 may be continued during this operation. By continuing the application of the vacuum after the tank 10 is empty, the excess liquid may be drawn off and 75

the filaments may be partially dried by the air drawn through the perforations in the bobbin.

It is of particular importance in the apparatus described that the liquid discharged from the tank 10 can only pass into the outlet corresponding to the filling line from which the tank was filled. As long as there is any liquid in the tank 10 or the well 63, the discharge line cannot be moved to another drain pipe. It may be desirable to start the withdrawal of the liquid from the tank 10 before the tank is completely filled. This may be accomplished with the arrangement described, since the outlet is through a line separate from the inlet line.

15 Although the invention has been described in connection with the use of three filling and discharge pipes, it is apparent that more or fewer filling or discharge pipes may be used, depending upon whether the material being treated is to be subjected to more or less operations. For example, more pipes may be added if it is desired to also use the apparatus for bleaching and for dyeing the threads or otherwise treating them. Also other actuating means may be used for operating the locking pin 66, for example, this may be accomplished by a spring and an electromagnet operated through a circuit opened and closed by the movement of the float 63 or by other suitable and well known means.

30 When the liquid is supplied continuously to the tank 10 while it is being withdrawn from that tank, the valve 13a, 13b or 13c may be left slightly opened or a bypass may be provided around the valve, as illustrated at 10b. This bypass may be provided with a valve 11b, which may be automatically operated by a float 72 in the tank 10, connected to the valve 11b by an electric or mechanical connection (not shown). Also, if it is desired to recirculate the liquid through the bobbins, the discharge line may be provided with a branch discharge line 13 having a valve 74 in order that the liquid may be run back to the tank 10. With this arrangement a portion or all of the liquid may be recirculated, the remainder being discharged.

45 It is apparent that the invention may be utilized in many different forms and for other liquid treating operations of a similar nature and that the steps of the procedure may be altered, and it is not intended to restrict it to the particular embodiment described. The terms used in describing and claiming the invention are used in their descriptive sense and not as terms of limitation and it is intended that all equivalents of these terms be included within the scope of the appended claims.

What we claim is:

1. An apparatus for treating threads upon receivers, comprising a tank adapted to receive perforated receivers and provided with means for withdrawing the liquid that passes through the threads and perforations in the receivers, separate conduits for supplying liquid to said tank and a swinging pipe adapted to connect the bottom of said tank with any one of said supply conduits.

2. An apparatus for treating thread wound upon receivers, comprising a tank adapted to receive tiers of perforated receivers and provided with outlets for withdrawing the liquid that passes through the threads and perforations in the receivers, separate filling lines for supplying different liquids to said tank, a swinging connecting pipe adapted to connect said tank with any one of said filling lines, a receiving tank for the

liquid withdrawn from said outlets, means for applying a vacuum to said receiving tank to draw liquid from the treating tank, means for withdrawing the liquid from said receiving tank under a higher degree of vacuum than that applied to the receiving tank to draw the liquid from the treating tank.

3. An apparatus for treating threads wound upon bobbins comprising a tank adapted to receive perforated bobbins and provided with means for withdrawing the liquid that passes through the perforations, separate feed lines for supplying different liquids to said tank and separate discharge lines for carrying liquid from said tank, a movable connection for connecting any of said filling lines with the said tank and a movable connection actuated with said filling connection and adapted to convey liquid discharged from said tank to any of said discharge lines.

4. An apparatus for circulating separate treating liquids through a tank comprising a plurality of filling lines having discharge outlets positioned in the arc of a circle, a plurality of discharge lines having inlet openings positioned in the arc of a circle, a pipe adapted to swing in the arc of a circle to connect any one of said filling pipes with the tank and a swinging discharge pipe actuated in accordance with the movement of said swinging connecting pipe for conveying liquid to an inlet in a discharge pipe.

5. An apparatus for circulating separate treating liquids through a tank comprising a plurality of filling lines for supplying liquid to said tank, a plurality of discharge pipes for receiving liquid from said tank, a swinging pipe adapted to convey liquid from any of said filling lines to the tank, a swinging discharge line adapted to convey liquid from the tank to any of said discharge lines, means for actuating said swinging discharge line with the swinging filling lines, and means for locking said swinging pipe in communication with any set of filling and discharge lines.

6. An apparatus for circulating separate treating liquids through a tank comprising a plurality of filling lines, a plurality of discharge lines, a swinging filling pipe adapted to convey liquid from any of said filling lines to the tank, a swinging discharge line adapted to discharge liquid from the tank to any of said discharge lines, means for actuating said swinging discharge pipe with said swinging filling line and a locking device actuated by a float in said tank for preventing movement of said swinging pipes while liquid is contained in the tank.

7. An apparatus for circulating liquids through a tank comprising a plurality of filling lines having downwardly disposed discharge outlets positioned in the arc of a circle, a plurality of discharge lines having upwardly disposed inlet openings positioned beneath said outlets, a pipe carried on a pivoted support and having an upper end adapted to swing in an arc beneath said outlets and a lower end adapted to swing in an arc above said inlets, an intermediate swiveled connection between the lower end portion of said swing pipe and the tank, said lower end being also provided with a valve normally closed, a telescopic sleeve at the upper end of said pipe adapted to be raised to surround an inlet opening from a filling line and means for raising and lowering said sleeve, a loose coupled rod connecting said sleeve with said valve, and a locking pin actuated by a float in said tank and adapted to hold said sleeve in a raised position while liquid remains in said tank.

8. An apparatus for treating with liquid comprising a tank, feed lines and discharge lines for said tank, a movable inlet connection and a movable outlet connection for said tank adapted to move together to put the tank in communication with any set of feed and discharge lines, and a locking device actuated by the liquid in the tank for controlling the movement of said inlet and outlet connection.
9. A swinging pipe for conveying liquids to a tank from several sources and also conveying liquid from said tank into a plurality of discharge lines comprising a pivotally supported pipe having an inlet at one end and being connected at its other end to the bottom of the tank by a pipe provided with a swivel connection, said first mentioned pipe having a discharge outlet in its lowermost portion, and a valve in said outlet for closing the same whereby when said valve is closed liquid will be conveyed to said tank and when open will permit liquid to discharge from said tank into said discharge lines.
10. An apparatus for treating tiers of material comprising a tank having a vertical partition near one end extending from above the level of the liquid to near the bottom of the tank, an inlet for liquid between said partition and the closest end, a horizontal baffle extending from said vertical partition above said inlet over a portion only of the end space, a pipe for conveying a liquid to said tank and means for discharging from the tank the liquid used in treating said material.
11. A container for treating tiers of material comprising a tank having a baffle extending from above the surface of the liquid to near the bottom of the tank, an inlet for liquid in the bottom of the tank on one side of said baffle, and a baffle extending from said first mentioned baffle to a position above the said inlet and covering only a portion of the space on that side of the first mentioned baffle.
12. A swing pipe for conveying liquids from any one of a plurality of outlets to a tank, comprising a pipe communicating at one end with the tank and adapted to swing into line with each of said outlets, a sleeve telescopically arranged relative to the inlet end of said swing pipe and means carried by said pipe for actuating said sleeve to move it into a position to operatively connect said swing pipe and the adjacent outlet.
13. A swing pipe as defined in claim 12, in which the sleeve comprises a flared end adapted to fit around the said adjacent inlet and an end adapted to fit within the swing pipe.
14. A swing pipe for conveying liquid from any one of a plurality of outlets to a tank, comprising a pipe communicating at one end with the tank and adapted to swing into line with each of said outlets, a sleeve telescopically arranged relative to the outlet end of said swing pipe and means for actuating said sleeve to move it into a position to operatively connect said swing pipe and the adjacent outlet, said sleeve comprising a flared end adapted to fit around the said adjacent inlet and an end adapted to fit within the swing pipe.
15. A swing pipe for conveying liquids from any one of a plurality of outlets to a tank, comprising a pipe communicating at one end with the tank and adapted to swing into line with each of said outlets, a sleeve telescopically arranged relative to the inlet end of said swing pipe, means for actuating said sleeve to move it into a position to operatively connect said swing pipe and the adjacent outlet, and means actuated by a float in said tank for locking said sleeve against movement out of engagement with said outlet while there is liquid in the tank.
16. A swing pipe for conveying liquids from any one of a plurality of outlets to a tank, comprising a pipe communicating at one end with the tank and adapted to swing into line with each of said outlets, a sleeve telescopically arranged relative to the outlet end of said swing pipe, means for actuating said sleeve to move it into a position to operatively connect said swing pipe and the adjacent outlet, said swing pipe being provided with a valve at its lower end operated by the movement of said sleeve.
17. A swing pipe for conveying liquids from any one of a plurality of outlets to a tank, comprising a pipe communicating at one end with the tank and adapted to swing into line with each of said outlets, a sleeve telescopically arranged relative to the outlet end of said swing pipe, means for actuating said sleeve to move it into a position to operatively connect said swing pipe and the adjacent outlet, said swing pipe being provided with a valve at its lower end operated by the movement of said sleeve and with means actuated by a float in said tank for locking said sleeve against movement out of engagement with the adjacent outlet when there is liquid in the tank, without interfering with the movement of said sleeve to open the valve at its lower end.
18. A swing pipe for conveying liquid to a tank from several sources positioned in the arc of a circle and for discharging liquid from the tank to a plurality of receivers in an arc of a circle about the same center, comprising a swinging pipe connected to said tank by a swivel joint in line with the common center of said circles, an inlet to said pipe adapted to swing in the arc of said sources and an outlet to said pipe adapted to swing in the arc of said receivers and a valve in said pipe adapted to open and close said outlet.
